UNITED STATES PATENT OFFICE.

EINO SAUKKONEN, OF ROSSLYN HEIGHTS, NEW YORK.

GARMENT HANGER.

Application filed October 11, 1920. Serial No. 416,042.

To all whom it may concern:

Be it known that I, EINO SAUKKONEN, citizen of Finland, residing at Rosslyn Heights, in the county of Nassau and State 5 of New York, have invented certain new and useful Improvements in Garment Hangers, of which the following is a specification.

This invention has relation to garment hangers, and has for an object to provide an 10 improved garment hanger upon which a suit, dress or the like may be supported with means whereby the trousers of a suit may be folded and supported in a manner to prevent the formation of creases and to ensure 15 the retent of the garment in proper relative position upon the support.

In addition to the foregoing this invention comprehends improvements in the details of construction and arrangement of 20 parts to be hereinafter described and particularly set forth in the appended claims.

In the accompanying drawings in which similar and corresponding parts are designated by the same characters of reference 25 throughout the several claims in which they appear,

Figure 1 is a view in perspective of a garment hanger constructed in accordance with my invention, and

30 Figure 2 is a view in vertical transverse section.

With reference to the drawings, 10 indicates an arcuate coat hanger having a hook shape member 11 provided centrally thereof 35 and formed of wire with one end of said member extending transversely through the coat hanger and projecting below the under side thereof and bent to form an eye 12. The trouser support is indicated at 13 and 40 consists of a roll of wood, paper or any other suitable material supported upon the in-turned end 14 of two wire strands. The opposite terminals of said wire strands being 45 bent and inserted into the ends of the coat hanger 10. The intermediate portion of each of the strands 14 is then bent inward to form loops 15 which are directed toward each other. I also provide a retaining means in the form of a rod 16 which is preferably 50 constructed of rubber or other flexible and resilient material and is provided at each end with an opening through which one of the loops 15 extend. A metallic band or the like 17 is embraced about the intermediate portion of the receiving member 55 and is provided with a hook shaped mem-

ber 18. It will be observed that normally the retaining member 16 lies in contiguous and close relation and preferably in parallelism to the roller 13.

In use, the retaining member is separated 60 from the roller 13 by flexing the same in the middle and engaging the hook 18 upon the eye 12. The trousers are now folded and laid upon the roller 13 and the retaining 65 member again released so as to permit it to spring back into contact with the trousers and securely retain them in position. The remaining portions of the clothing are now suspended upon the coat hanger 10 as shown 70 in dotted lines in Figure 1. It will be observed that owing to the provision of the roller 13 the formation of a transverse crease in the trousers is prevented and also the trousers may be readily removed therefrom 75 by merely drawing them away, rotation of the roller 13 facilitating this process.

While I have illustrated and described my invention with some degree of particularity I realize that in practice various alterations 80 therein may be made. I therefore reserve the right and privilege of changing the form of the details of construction or otherwise altering the arrangement of the correlated parts without departing from the 85 spirit of the invention or the scope of the appended claims.

Having thus described my invention what I claim as new and desire to secure by 90 United States Letters Patent is:—

1. A garment support including a coat hanger portion a member supported thereon upon which to rest another garment, and a retaining element in the form of a straight rod of resilient material anchored at its ends 95 to the ends of the coat hanger portion and extending in close contiguous relation to said member, whereby the retaining element may be flexed and stretched away from the member to insert the garment therebetween.

2. A garment support including a coat hanger portion an arm extending from each end of said portion, a roller journaled between the ends of said arms, and a straight rod of resilient material interposed between the coat hanger portion and roller, said rod being anchored at its ends to said arms and extending in close contiguous relation to the roller whereby said rod may be flexed and slightly lengthened by stretching to permit 110 the insertion of a garment between the rod and roller.

3. A garment support including a coat hanger portion, a member supported therefrom upon which to rest another garment, a straight rod of resilient and elastic material anchored at its ends to the ends of the coat hanger portion and the ends of said member, and means to secure the intermediate portion of the rod to the coat hanger portion when said rod is flexed away from the member and lengthened by stretching, so that a garment may be rested on the member and said means disconnected to permit the rod to return to normal position to retain the second garment on said member.

4. A garment support including a coat hanger portion, a pair of arms extending from the ends of the coat hanger portion, a roller supported upon and between the ends of the arms for rotation, a loop formed in each arm, and a rod of resilient and elastic material having an opening at each end to

receive one of the loops so that said rod may extend in close parallel relation to the roller.

5. A garment support including a coat hanger portion, a hook secured therein to suspend the same, an eye on said hook, a roller supported from the coat hanger portion, a straight rod of elastic and resilient material anchored at its ends to the coat hanger portion, and a hook secured to the intermediate portion of the rod and adapted to enter the eye when the rod is flexed and stretched away from the roller to permit a garment to be inserted between the rod and roller.

In testimony whereof I affix my signature in the presence of two witnesses.

EINO SAUKKONEN. [L. s.]
